[57] CLAIM

The ornamental design for a portable automated teller machine, as shown and described.

DESCRIPTION

FIG. 1 is a top, and right-front perspective view of a portable automated teller machine in an open position showing my new design, the bottom view being flat and unornamented.

FIG. 2 is a top plan view thereof;

FIG. 3 is a top plan view of FIG. 4 in a closed position; FIG. 4 is a front elevational view of FIG. 3; and, FIG. 5 is a side elevational view of the right-hand side of FIG. 3, the left side being a mirror image thereof.

FIG. 1

FIG. 2

FIG. 3

FIG. 4

FIG. 5
